UNITED STATES PATENT OFFICE.

FRANK A. HOWARD, OF WESTFIELD, NEW JERSEY, ASSIGNOR TO STANDARD DEVELOPMENT COMPANY, A CORPORATION OF DELAWARE.

ART OF OPERATING WATER-GAS GENERATORS.

Application filed April 1, 1920. Serial No. 370,510.

My invention relates to the manufacture of water gas and will be fully understood from the following specification taken in connection with the accompanying drawing 5 which shows in diagrammatic vertical section, a form of water gas generator, suited to the purposes of the present invention.

In the drawing the numeral 1 designates the steel shell of the water gas generator, this shell being lined with fire brick 2, or other heat insulating and resisting material. Some distance above the bottom of the generator are located grate bars 3. The frusto-conical top of the generator, designated 4, is 15 closed by a cover plate 5 in the usual manner. A valved conduit 6 leads from the upper portion of the generator and a similar conduit 7 enters the chamber below the grate bars 3. In addition to these, there is a 20 third conduit 8 disposed substantially midway of the height of the generator and communicating with the latter by tuyeres 9 perforating the lining 2. An oil spray pipe 10 enters the casing of the generator near the 25 cover plate and is arranged at such an angle as to permit uniform distribution of the sprayed oil over the upper surface of the coal or coke in the generator. A steam supply pipe 11 is preferably tapped into the side of the oil pipe 10 to secure more efficient spraying of the oil, and for other 30 purposes as will later appear.

In accordance with my invention, the above described gas generator may be operated in the following manner.

The generator is charged with a good grade of gas coal, in lumps not too small, or with coke, and fired in the usual manner. The air blast enters through the lower conduit 7, passing through the grate bars 3, and upward through the lower section of the coal bed, thence out by the tuyeres 9 and conduit 8. Blasting will be conducted in this manner until a temperature of the fuel 40 bed proper for the production of water gas is obtained. The blast will then be shut off and the steam required for the production of the water gas will be introduced, as for example, by a pipe 7' tapped into the pipe 50 7. During the water gas making period, the valve in the pipe 8 will be left open, the valve in the pipe 6 remaining closed. The generated water gas will therefore pass out through the pipe 8 to be further handled 55 in a manner which does not concern the

present invention. At the end of the water gas making period the steam supply will be shut off, the valve in pipe 8 closed, the valve in the pipe 6 opened, and oil introduced, with or without steam, through the supply pipe 10. The introduced oil will be distributed more or less uniformly over the surface of the fuel in the top of the generator, and will be vaporized by the heat of this fuel body. Accordingly, as the height 60 of the fuel bed above the tuyeres 9 is great or small, the vaporization temperature to which the oil is subjected, will be low or high. That is, if vaporization at a low temperature and with a minimum amount of 65 cracking of the oil is to be accomplished, the fuel level will be maintained very near the top of the generator, that is, a considerable distance above the tuyeres 9. On the contrary, if the vaporization is to be attended by a greater amount of cracking, or decomposition of the oil, a lower fuel level will be maintained. By way of explanation of these statements, it may be remarked that the body of fuel lying above the tuyeres 70 9 is heated almost entirely by conduction in the cycle of operation above described, and the temperature of its upper surface is therefore a function of the depth of the conducting bed. A further control of the amount 75 of decomposition attending the vaporization of the oil may be had by varying the quantity of steam used for injecting the oil. A still further control of the character of the vaporization accomplished in the top of the 80 generator may be had by introducing steam through a pipe 8' tapped into the conduit 8. The steam thus introduced passes outward from the tuyeres 9 and upward through the body of fuel lying above the tuyeres, effecting 85 steam reduction of that portion of the oil which trickles through the fuel bed and hence escapes the direct action of the steam injected upon the surface of the bed.

The oil vapors accompanied by a greater 90 or less proportion of fixed gas according as the amount of decomposition is large or small, pass from the generator through the upper conduit 6. These vapors may be in part or wholly condensed or may be cracked 95 for the production of oil gas, the further handling of the vapors not constituting part of the present invention.

The process above described is mainly designed for the handling of heavy asphaltic 100 110

base petroleum oils, either heavy crude petroleum, such as the 12° Bé. gravity crude oil produced in the Panuco district of Mexico, or residues from lighter crude petroleums. By the process described, such crude petroleum oils may be subjected to distillation with a governed amount of simultaneous cracking, varying from a maximum to a minimum amount of fixed gas by the controlled process described. As an inevitable incident of the process, the large proportion of coke produced in the distillation of the oil down to dryness is deposited within and upon the coal or coke with which the generator is charged. As so deposited, it is available for the production of the water gas, the continuation of the process above described, with the intermittent addition of fresh fuel, serving to work the fuel bed constantly downward in the ordinary fashion. Within a short time after the operation begins therefore, the fuel within the generator consists of coal or coke from coal, permeated and coated by petroleum coke produced in the upper chamber of the generator.

The three phase cycle of operation above described, may be varied considerably, both as to the number of phases and as to the conduct of each phase. For example, a further control of the temperature of the fuel bed in the top of the generator may be attained by permitting part of the air blast gas to escape through the pipe 6 during the blowing-up of the generator. Likewise, it is permissible to cause the oil vapors to pass outward through the pipe 8 instead of the upper conduit 6, that is, to force these vapors to traverse the whole depth of the upper fuel bed before escaping. It is also feasible to introduce the steam for the water gas make through the steam line 8', causing it to pass downwardly through the generator, so that the generated water gas will escape from the conduit 7. Under this condition of operation, the process may be conducted in two phases, the oil being sprayed on to the top of the fuel bed simultaneously with the introduction of steam in 8'. Under these conditions a mixture of water gas and oil gas will be delivered from the lower conduit 7.

The foregoing will, it is believed, be sufficient to indicate the scope of usefulness

of the present invention, and the manner in which the particularly described procedure may be varied while still adhering to the same underlying principles of operation.

What I claim is:

1. The improvement in the art of operating water gas generators which consists in bringing the fuel in one section of a water gas generator to the temperature required for water gas generation, simultaneously bringing the fuel in another section of the generator to a temperature at least suitable for the vaporization of petroleum oil, producing water gas in the first section, subsequently introducing petroleum oil into said second section, separately removing the vapors formed by said petroleum oil vaporization, and causing the fuel in said second section, with the petroleum coke deposited therein, to move into said first section.

2. The improvement in the art of operating a water gas generator which consists in dividing the fuel in such generator into two superimposed zones, air blasting the lower zone separately, independently controlling the temperature of the upper zone, producing water gas in the lower zone, then introducing oil into the upper zone, and separately removing the vapors formed in said upper zone therefrom.

3. The improvement in the art of operating water gas generators which consists in dividing the fuel bed in a water gas generator into two zones, alternating air blasting the lower zone and passing steam through the lower zone for making water gas, and introducing petroleum oil into the upper zone after the water gas making period and prior to blasting the lower zone.

4. The improvement in the art of operating water gas generators which consists in dividing the fuel bed in a water gas generator into two zones, alternating air blasting the lower zone and passing steam through the lower zone for making water gas, introducing petroleum oil into the upper zone subsequent to the water gas making period and prior to blasting the lower zone, and separately removing the vapor material formed from the petroleum oil in the upper zone.

FRANK A. HOWARD.
